UNITED STATES PATENT OFFICE.

JOHN H. ANNIS, OF HILLSBORO, NEW HAMPSHIRE, ASSIGNEE OF ONE-HALF TO
CHARLES W. HENRICKSON, OF JACKSONVILLE, FLORIDA.

RAILROAD-SPIKE.

1,112,532

Specification of Letters Patent.

Patented Oct. 6, 1914.

Application filed September 24, 1912. Serial No. 701,832.

To all whom it may concern:

Be it known that I, JOHN H. ANNIS, a citizen of the United States, residing at Hillsboro, in the county of Hillsboro and State of New Hampshire, have invented certain new and useful Improvements in Railroad-Spikes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to railroad spikes and has for its object to provide a spike for securing the usual metallic rail to the usual wooden cross tie, and the invention has for its object to provide a spike which is so shaped and arranged that when the same is driven home it will more rigidly engage the foot of the rail to prevent same from moving and to insure against spreading of the rail.

With this object in view the invention consists in the novel construction of the railroad spike, and the invention consists particularly in the novel construction of the T head of the spike which causes the same to more rigidly engage the foot of the rail and to approach the same as the spike reaches the limit of its drive.

The invention further consists in the construction of the spike which adds strength to the same, prevents lateral movement of the spike and produces an article which for strength and rigidity is superior to articles of this class.

Referring to the accompanying drawing: Figure 1 is a vertical transverse sectional view through a railroad rail illustrating the spike in elevation and illustrating the same in position about to engage the foot of the rail, and Fig. 2 is a similar view illustrating the position of the spike shown in dotted lines as is illustrated in full lines in Fig. 1 and showing the spike in full lines in Fig. 2 illustrating the same in engagement with the foot of the rail, and further illustrating the same as having approached the foot of the rail to more tightly engage the same.

Like numerals of reference indicate the

same parts throughout the two figures in which:

1 indicates the rail having the usual tread 55
2, web 3 and foot 4.

5 indicates the wooden cross tie and 6 indicates the spike.

As shown in the accompanying drawing the spike 6 comprises the shank 7 pointed at 8 and provided with a T head 9, the T head 9 comprising the inclined projecting portion 10 which engages the foot of the rail and comprising the deep inclined projecting portion 11 which engages the tie 5 in the manner as will be now described. It will be noted that the projecting portion 11 also comprises a vertical wall 12, the inclined surface of the projecting portion 11 being indicated by the numeral 13.

Having thus described the several parts of this invention its operation is as follows: The spike being driven into the tie in the manner as illustrated in Fig. 1 when the said spike reaches the position illustrated in Fig. 1 the inclined surface 13 of the projecting portion 11 of the head 9 engages the surface of the wooden tie 5 at the point 14, the projecting portion 10 of the head 9 so projecting over the edge of the foot 4 as clearly shows in Fig. 1. When, however, the spike is driven into its extreme position, as shown in full lines in Fig. 2, the inclined surface 13 of the extension 11 of the head 9 acts upon the surface of the tie 5 and as this inclined portion 13 engages the said surface the head portion of the spike is caused to move in a transverse direction toward the foot 4 of the rail in the manner as is clearly shown in Fig. 2, and when the said spike is in its lowermost position, as shown in full lines in Fig. 2, the vertical wall portion 12 of the extension 11 of the head 9 enters the wooden tie 5 as illustrated at 15 in Fig. 2, thus holding the said head 9 of the spike against lateral movement in a direction away from the foot 4 of the rail.

By means of this construction the spikes are caused to more tightly and rigidly engage the foot of the rail to prevent transverse movement thereof and to prevent any spreading or loosening of the rail; while the construction of the head 9 adds a great amount of strength to the spike causing the same to withstand shocks and vibrations

which under usual conditions have a tendency to loosen the spikes and in some instances break the same. By means of this construction, however, the strength of the spike is not only greatly enhanced but its holding power is increased and the rigidity of the rail in relation to the tie is greatly enhanced.

Having thus described this invention it is apparent that certain changes can be made therein which would fall within the limit and scope of this invention, and I consider myself clearly entitled to all such changes and modifications as fall within the limit and scope of the appended claim.

What I claim as new and desire to secure by Letters Patent of the United States is:—

A railroad spike comprising a pointed shank and a T head, said T head comprising a projecting portion having an inclined bottom for engagement with the foot of a railroad rail and also comprising a projecting portion having an inclined bottom for engagement with the upper surface of a

wooden cross tie, said last mentioned projecting portion having also a vertical wall adapted to enter the railroad tie to prevent transverse movement of the spike, the said last mentioned projecting portion being thicker than the first mentioned projecting portion whereby the said inclined bottom thereof will engage the wooden tie before the said inclined surface of the first mentioned projecting portion will engage the surface of the rail, the whole arranged in such manner that when the said spike is driven into its extreme lowermost position the said inclined surface on the second mentioned projecting portion will engage the surface of the tie to cause the spike to move transversely toward the rail, substantially as described and for the purposes set forth.

In testimony whereof I affix my signature, in presence of two witnesses.

JOHN H. ANNIS.
